UNITED STATES PATENT OFFICE.

STEPHEN A. MORGAN, OF COALGATE, INDIAN TERRITORY, ASSIGNOR OF
ONE-THIRD TO JOSEPH A. BOGY, OF SAME PLACE.

DESIGN FOR A TUG-FASTENER.

SPECIFICATION forming part of Design No. 33,789, dated December 25, 1900.

Application filed November 6, 1900. Serial No. 35,676. Term of patent 14 years.

To all whom it may concern:

Be it known that I, STEPHEN A. MORGAN, a citizen of the United States, residing at Coalgate, Choctaw Nation, Indian Territory, have 5 invented and produced a new and useful Design for Tug-Fasteners, of which the following is a specification.

My invention relates to tug-fasteners; and my object is to produce a new and useful design for the same.

In the accompanying drawings, Figure 1 represents an end view of a tug-fastener embodying my design. Fig. 2 is a front view of the same. Fig. 3 is a perspective view of the 15 same. Fig. 4 is a plan view of the same.

As shown, the leading or material feature of the design consists in its peculiar shape or configuration, the same resembling the letter S when viewed from the end, the same letter 20 with a laterally-projecting cross-bar or arm when viewed in perspective, a vertical elliptical loop having a horizontal cross-bar when viewed from the front, and an obtuse angle with laterally-projecting arms when viewed 25 from above.

Minor features of the design reside in the pointed inner end of the cross-bar or arm, in the pointed free end of the body portion of the figure, and in the approximately elliptical 30 shaped head at the outer end of said cross-bar or arm.

Referring to the drawings in detail, the central part of the body portion of the figure numbered 1 extends substantially downward and forward. The lower half of said portion 35 in conjunction with the upwardly-projecting pointed portion 2 forms the upwardly-disposed hook or loop 3, while the upper part of said portion in conjunction with the downwardly-projecting arm 4 forms a downwardly-disposed hook or loop 5, the terminals of said portions 2 and 4 occupying about the same horizontal plane. The portion 4 forms a junction at its lower end with the horizontal arm 6, which projects to the left and terminates 40 in a pointed end 7 and to the right and terminates in a tapered elliptical head 8, said head extending at an angle of about forty-five degrees to the perpendicular.

Having thus described my invention, what 50 I claim as new, and desire to secure by Letters Patent, is—

The design for a tug-fastener substantially as herein shown and described.

In testimony whereof I affix my signature 55 in the presence of two witnesses.

STEPHEN A. MORGAN.
